UNITED STATES PATENT OFFICE.

JAMES G. CARY, OF JACKSON, TENNESSEE.

WATER-CLOSET ATTACHMENT.

1,051,985.

Specification of Letters Patent. Patented Feb. 4, 1913.

Application filed May 18, 1912. Serial No. 393,225.

To all whom it may concern:

Be it known that I, JAMES G. CARY, a citizen of the United States, residing at Jackson, in the county of Madison and 5 State of Tennessee, have invented new and useful Improvements in Water-Closet Attachments, of which the following is a specification.

This invention relates to improvements 10 in water closet attachments, and more particularly to sanitary seats for closets.

It is the object of this invention to provide an attachment to water closet seats, whereby a fresh sanitary seat may be supplied between each time of use.

This invention is of great advantage in all public toilets from a sanitary standpoint, and may be readily applied to closet seats now in use with but little change, or 20 to the closets by a specially constructed seat. As the sanitary covering for the seat is preferably of paper but little expense is attached. The sheets may be in tablet form, that is, one of their edges bound or 25 glued together, and the top sheet removed before using. The sanitary seats are renewable as easily as the toilet paper box holders now in use in public toilets, and should the sanitary seats become exhausted 30 the function of the seat proper is not destroyed.

While the preferred forms of this invention are illustrated upon the accompanying sheet of drawing, yet it is to be 35 understood that minor detail changes may be made without departing from the scope thereof.

Figure 1 is a view in perspective of one form of this invention. Fig. 2 is a top plan 40 view of Fig. 1. Fig. 3 is a view in section taken on the line 3—3 of Fig. 2. Fig. 4 is a detail plan view of the blanks used with the seat illustrated on Fig. 1. Fig. 5 is a top plan view of another form. Fig. 6 is 45 a view in section taken on the line 6—6 on Fig. 5. Fig. 7 is a view in section taken on the line 7—7 on Fig. 5. Fig. 8 is a fragmentary view in side elevation of Fig. 5. Fig. 9 is a top plan view of a modification. 50 Fig. 10 is a view in section on the line 10—10 on Fig. 9. Fig. 11 is a view in section on the line 11—11 on Fig. 9. Fig. 12 is a detail plan view of the blanks used with the seat illustrated on Fig. 5. Fig. 55 13 is a detail plan view of the blanks used with the seat illustrated on Fig. 9.

The form illustrated on Fig. 1 employs a special seat. The seat proper 1 is of usual shape and is attached to the closet 2 in the usual manner, and may be of wood, 60 metal or any other desired material. Beginning a short distance from a longitudinal center line at the back an aperture is provided which, in proximity to the outer edge, follows the contour of the seat proper 65 on each side and terminates a short distance from the longitudinal center line in front and a similar aperture is provided in proximity to the inner edge of the seat proper. The central portion 3 is slightly depressed 70 and is curved so that its sides are below the outer and inner portions of the seat proper, with the lower edges resting upon the top of the closet. The outer portions 4 are flat with their under side in the same plane as 75 the crown of the curved central portion 3. The inner portions 5 are curved downwardly and inwardly from the plane of the portion 4 and then downwardly and outwardly with the lower edges in proximity 80 to the adjacent lower edges of the central portion 3. This construction provides a means for detachably holding blanks of sanitary paper 6 cut in conformity to the contour of the seat proper with their outer 85 edges extending through the apertures between the outer flat portion and the central portion and their inner edges extending through the apertures between the central portion and the inner curved portion. 90 The curved portion 3 causes the central portion of the blank to extend above the plane of the seat proper providing a sanitary seating surface. It is preferable that this seat be formed of metal or resilient 95 material, so that a plurality of sections of sanitary blanks may be applied one above the other and they will be firmly held in place, yet allow of the removal of the upper blank one at a time until exhausted. 100

The forms illustrated in Figs. 5 to 13 may be applied to seats now in use. A spring clip 10 is secured to the under side of the front and back of the seat proper upon the longitudinal center line having the bow of 105 the spring extending about the inner edge of the seat and provided upon the top, with an engaging plate 11. A spring member 12 is also secured on each side to the under side of the seat proper having a flat portion engaging the central outer portion of the seat, as shown in Fig. 5. The blanks 13 for this 110

form are provided at their meeting edges with a cut-away portion 14 to surround the bow of the spring 10 and allow the adjacent ends to meet and be clamped in place under 5 the plate 11 upon the upper end of the spring 10. Projecting ears 15 are provided upon each outer edge which are adapted to extend downwardly at the edge of the seat proper and be engaged by the flat portion 10 of the side springs 12. Lines of perforations 16 are provided on each blank from the cut-away portion to the outer edge, so that while the spring plate 11 firmly engages the end portion and the main portions 15 are held in place by side springs 12, the top blank may be readily removed without disturbing the others by tearing through the line of perforations.

The form shown on Fig. 9 illustrates a 20 slightly different form in which the blanks 20 are wider and are of the same contour as the seat proper with their meeting edges held under the plate 11^a of the detachable spring 10^a secured in the manner as shown 25 in Fig. 11. In the form a line of perforations 21 is provided across each end so that while the adjacent ends of the blanks are held in place yet the top one may be readily 30 removed by tearing through the perforations without disturbing the others. This form may be applied to seats now in use or 35 the seat proper 1^a may be of a malleable casting of greatly less cost, and may or may not be provided with a pad or cushion 1^b, as shown in Figs. 10 and 11.

What I claim is:

1. A sanitary seat protector for closets comprising a plurality of sanitary blanks one above the other arranged in sections on 40 each side of the center line of the seat, each section having a line of transverse perforations across each end, the adjacent end portions of the sections adapted to be firmly engaged and held in place upon the upper 45 surface of the seat but allow of a removal of the main section by tearing through the line of perforations at each end thereof.

2. A sanitary seat protector for closets comprising a plurality of sanitary blanks 50 one above the other arranged in sections on each side of the center line of the seat, each section having a line of transverse perforations across each end, the adjacent end portions of the sections adapted to be firmly 55 engaged and held in place upon the upper

surface of the seat but allow of a removal of the main section by tearing through the line of perforations at each end thereof, and each blank having a projection extending from the middle of the outer side of the 60 blank at an angle to the center line of the seat adapted to be engaged by resilient means to normally hold said main portions of the protector in place on each side of the seat.

3. As an article of manufacture a blank 65 of sanitary material for protecting closet seats of similar contour to the seat which when in place will terminate short of the center line of the closet at each end, the 70 adjacent ends of said blank provided with a cut out portion between the inner and outer edges of each blank adapted to surround a means for securing the blanks to the top of the seat.

4. As an article of manufacture a blank 75 of sanitary material for protecting closet seats of similar contour to the seat which when in place will terminate short of the center line of the seat at each end, and having 80 a line of perforations parallel to and in proximity to each end.

5. As an article of manufacture a blank 85 of sanitary material for protecting closet seats of similar contour to the seat which when in place will terminate short of the center line of the seat at each end, the adjacent end of each blank provided with a cut out portion between the inner and outer edges thereof adapted to surround a means 90 for securing the blanks to the top of the seat, and having a projection extending from the middle of the outer side of the blank at right angles to the center line of the seat adapted to be engaged by a means 95 for securing each blank to the side of the seat.

6. As an article of manufacture a blank 100 of sanitary material for protecting closet seats of similar contour to the seat which when in place will terminate short of the center line of the seat at each end, having a line of perforations parallel to and in proximity to each end, and having a projection 105 extending from the exterior side thereof.
